US00D741800S

(12) **United States Design Patent**
Yonishi et al.

(10) **Patent No.:** US D741,800 S
(45) **Date of Patent:** ** Oct. 27, 2015

(54) **RECHARGEABLE BATTERY**

(71) Applicant: **Sony Corporation**, Tokyo (JP)
(72) Inventors: **Kiyoshi Yonishi**, Fukushima (JP);
Atsuhiro Kumagai, Kanagawa (JP)
(73) Assignee: **Sony Corporation**, Tokyo (JP)
(**) Term: **14 Years**
(21) Appl. No.: **29/521,679**
(22) Filed: **Mar. 25, 2015**
Related U.S. Application Data

(63) Continuation of application No. 29/497,846, filed on Jul. 29, 2014, which is a continuation of application No. 29/462,492, filed on Aug. 5, 2013, now Pat. No. Des. 711,826, which is a continuation of application No. 29/442,045, filed on Nov. 21, 2012, now Pat. No. Des. 687,777.

(57) **CLAIM**

The ornamental design for a rechargeable battery, as shown and described.

DESCRIPTION

FIG. 1 is a rear elevational view of a rechargeable battery showing our new design;

FIG. 2 is a left side elevational view thereof;

FIG. 3 is a right side elevational view thereof;

FIG. 4 is a top plan view thereof; and,

FIG. 5 is a bottom plan view thereof.

Broken lines illustrate unclaimed portions of the rechargeable battery and form no part of the claimed design.
